RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT-REPLENISHING MECHANISM FOR LOOMS

Application filed September 12, 1928. Serial No. 305,430.

This invention relates to improvements in weft replenishing mechanism for looms and it is the object of the invention to provide improved means for holding reserve bobbins in such mechanism while they await transfer.

In the usual form of multicolor weft replenishing mechanism the reserve bobbins are held in a plurality of vertical stacks or compartments, the bobbins moving downwardly by gravity toward transfer position. It is found that in some instances, due to the vibration of the loom, the bobbins will rotate on their axes to such an extent as to tighten the end which extends from the bobbins to the thread holder. When this happens the thread is likely to be broken at the time of transfer, with the result that the loom will stop through the action of the filling stop motion and the continuous operation which the replenishing mechanism seeks to insure is interrupted. It has been proposed heretofore to shape the butts of the bobbins so that they will cooperate with a device which will prevent them from rotating. Such means may have a wire extending parallel to and projecting into a bobbin compartment and lying in grooves cut in the butts of the bobbins.

While this method is effective in most instances to prevent rotation of the bobbins yet when the yarn diameter of the bobbin is less than the butt diameter the upper bobbins of the magazine are rather steeply inclined, the tip ends of the bobbin sloping downwardly to such an extent that the slotted part of the bobbin butts move away from the restraining wire. The result is that although the magazine or replenishing mechanism is capable of storing a comparatively large number of bobbins yet as a matter of fact three or four bobbins are found to be the maximum which can be safely placed in any one compartment.

It is an important object of my present invention to provide means for separating the bobbins in any one compartment into relatively small groups, the uppermost bobbin of each group being disposed at a sufficiently small angle so that the slotted butt thereof will properly cooperate with the restraining element.

In co-pending application Ser. No. 294,617, filed by Geronimo there is shown an attachment or trip for each compartment effective to enlarge the effective capacity of a weft replenishing mechanism operating with bobbins having yarn diameter less than the butt diameters, and it is a further object of my present invention to combine the device shown in said co-pending application with a bobbin restraining device operating to prevent rotating of the bobbins.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a front elevation of a portion of a weft replenishing mechanism having my invention applied thereto, and

Fig. 2 is a top plan view taken in the direction of arrow 2, Fig. 1 and showing a portion of the magazine shown in Fig. 1.

Referring to the drawings, I have shown a magazine M as being formed of an inside plate 10 and an outside plate 11, the inside plate being provided with substantially parallel vertical flanges 12 which define bobbin guideways or compartments 13 for the butts 14 of the bobbins B. The plate 11 is correspondingly formed with flanges 15 which define bobbin guideways or compartments 16 to receive the tips 17 of the bobbins B. The butts of the bobbins are provided with the usual steel split rings 18 which are received by the shuttle springs not shown of the type customarily employed on replenishing looms.

At the bottom of each of the compartments or guideways is pivoted a rotatable element known in the trade as a "cradle", being shown herein at 20 as having bearings 21 and 22 in the plates 10 and 11, respectively. By mechanism not shown but well understood the cradles are given a partial rotation upon indication of substantial exhaustion of weft in the active shuttle and when the indicating shuttle again returns to the magazine side

of the loom the cradles are rocked back to their original position to discharge the lowermost bobbin of the corresponding stack. A thread holder T is secured to the plate 11 and has secured thereto the ends W of weft extending from the reserve bobbins.

The matter thus far described is of common construction, forming no part of my present invention, and may be substantially 10 the same as set forth in the patent to Ryon No. 1,030,748.

In carrying my invention into effect I provide each of the plates 10 and 11 with elements which cooperate to enable the magazine 15 to accommodate more reserve bobbins than is possible with the usual magazine when the bobbins are wound as set forth herein. It will be seen by referring to the drawings that the yarn portion Y of the bobbins is considerably less in diameter than the butts 14 or the rings 18 and as a result the bobbins are inclined as suggested in Fig. 1, the tips of the upper bobbins being below their corresponding butts. As previously stated the 25 effect of this is to permit the butts of the bobbins to move away from the plate 10.

The butt of each bobbin is provided with a slot 30 which preferably extends diametrically across the outer face of the butt and 30 each compartment is provided with a restraining wire 31 which may be secured at the upper and lower portions thereof as at 32 and 33, respectively, to that part of the plate defining a part of the corresponding compartment. Under normal conditions the reserve bobbins lying above the cradles 20 will be related to the wire 31 as set forth in Fig. 2, said wire effectively preventing rotation of the bobbins on their axes and thereby preventing 40 entanglement of the weft ends W which extend to the thread holder T.

In each compartment 16 for the tips of the bobbins there is located a trip 40 which projects into the compartment 16 a slight distance. The trip is located at the proper distance above the cradles 20 so as to separate the bobbins into two groups as shown herein, although as set forth in the aforesaid application, I am not restricted to one trip but 50 may use as many as are found necessary depending upon the height of the magazine.

In operation, the cradle or control member 20 will be acted upon by a mechanism not shown to discharge the bobbins of the 55 corresponding stack one at a time so that the bobbins may move toward transfer position. During the time that the reserve bobbins above the member 20 are awaiting transfer the magazine will be subject to more or less 60 rotation due to jarring and vibration of the loom, but because of the wire 30 the bobbins will be prevented from rotating upon their axes and the weft ends W will not become entangled with each other. As the bobbins 65 move downwardly toward the member 20 the

trip 40 will be engaged by them and said trip will act to separate the bobbins into two groups. The uppermost bobbin of each group, while inclined as suggested in Fig. 1 will nevertheless be near enough to a horizontal position to have proper engagement with the wire 30. The lowermost bobbin of the upper group will be supported in part by the butts of the bobbins therebelow and in part by the trip 40, the lowest bobbin in the upper group being disengaged from the trip as it moves downwardly toward the cradle 20.

From the foregoing it will be seen that the trip 40 cooperates with the bobbins to hold the latter in relatively small groups so that the uppermost bobbin of each group, while inclined, will be in the position to be properly engaged by the restraining wire 30. While I have shown the wire 30 as entering slots in the bobbin butts yet I do not wish to be limited to this particular form of device for preventing rotation of the bobbins.

Having thus described my invention it will be seen that changes and modifications may be made therein by those skilled in the art without departing from the spirit and scope of the invention and I do not wish to be limited to the details herein disclosed, but what I claim is:

1. In a weft replenishing magazine operating with bobbins the butts of which are each provided with a non-cylindrical surface extending substantially parallel to the axis of the bobbins, the yarn on the bobbins being wound to a diameter less than the diameter of the bobbin butts, a guideway for the butts of the bobbins, a second guideway for the tips of the bobbins the bobbins moving down the guideways by gravity, a device extending along the guideway for the butts to engage the non-cylindrical surfaces and prevent rotation of the bobbins about their axes, and stationary means located along the guideway for the tips of the bobbins to engage the tips and prevent such an inclination of the bobbins in the upper part of the guideways as would move the non-cylindrical surfaces of the bobbin butts away from the device.

2. In a weft replenishing magazine operating with bobbins the butts of which are each provided with a non-cylindrical surface extending substantially parallel to the axis of the bobbins, the yarn on the bobbins being wound to a diameter less than the diameter of the bobbin butts, means to engage the non-cylindrical surfaces to prevent rotation of the bobbins on their axes and a stationary device to hold the upper bobbins in the magazine in proper angular position to insure engagement of the means and non-cylindrical surfaces.

3. In a weft replenishing magazine operating with bobbins the butts of which are each provided with a non-cylindrical surface extending substantially parallel to the axis of

the bobbins, the yarn on the bobbins being wound to a diameter less than the diameter of the bobbin butts, a guideway for the butts of the bobbins, a second guideway for the tips of the bobbins the bobbins moving down the guideways by gravity, a device extending along the guideway for the butts to engage the non-cylindrical surfaces and prevent rotation of the bobbins about their axes, a stationary trip projecting into the guideway for the tips of the bobbins located in the upper part of the magazine to hold the bobbins in proper angular position to insure engagement of the device and non-cylindrical surfaces.

4. In a weft replenishing magazine operating with bobbins having radial slots extending across the end of the butt thereof, the yarn diameter of the bobbins being less than the butt diameter, a guideway for the bobbin butts, an elongated member extending into the guideway to enter the radial slots of the bobbin butts to restrain rotation of the bobbins on their axes, a second guideway for the tips of the bobbins the bobbins moving down the guideways by gravity, and a stationary trip extending into the second guideway to engage the tips of the bobbins as they pass along the guideways, said trip holding the bobbins thereabove in such angular position as to insure holding the member in the slots.

In testimony whereof I have hereunto affixed my signature.

35 RICHARD G. TURNER.
